UNITED STATES PATENT OFFICE

ALBERT L. NYLANDER, OF BLUE ISLAND, ILLINOIS

VISE-OPERATING MECHANISM

Application filed July 21, 1930. Serial No. 469,334.

My present invention relates to vise operating mechanism and has for its object the provision of instrumentalities which will enable a bench worker to operate the standard form of iron or steel bench vise with the foot, instead of the screw now generally employed, so that the bench worker will have both hands available for inserting into and removing the work from the vise, or if these operations can be done with one hand, the operator need not lay down his tool when relocating the work or inserting a new piece of work in the vise.

With modern manufacturing methods where the same operation has to be done on a number of articles my apparatus will be found a great economizer of time and effort.

Also, as will hereafter be seen, I have provided instrumentalities for controlling the pressure exerted by the vise jaws so that when the apparatus is adjusted as desired the jaws will close with exactly the same pressure until a new adjustment is made. This, also, is a great advantage as it obviates the bending or breaking of the work through the undue tightening of the vise.

As will hereafter be seen, my apparatus may be easily assembled with old bench vises of standard designs as well as being capable of being built into new vises, and to facilitate its shipment for installation in old vises, I have made the treadle arm of the operating lever detachable so that the apparatus may be put in a relatively small package for shipping.

I attain the foregoing objects and results by means of the structure illustrated in the accompanying drawing, in which—

Fig. 1 is a side elevation of a vise mounted upon a work bench with my invention assembled therewith.

Fig. 2 is a longitudinal central section of a portion of the base and the stationary and movable jaw.

Fig. 3 is a transverse section on line 3—3 of Fig. 2.

Similar reference characters have been employed for designating similar parts throughout the respective views.

The present standard form of metal bench vise, with which my apparatus is associated,

comprises a stationary jaw 10 integral with a base 11 which is bolted or otherwise secured to the bench and which base is transversely slotted to receive a reciprocable slide arm 12 on the outer end of which is provided, usually integral with the slide arm, the movable jaw 13 of the vise. Just below the transverse slot is provided integral with the base a projection or bracket 14 to assist in supporting the slide arm and movable jaw 13 when the latter is in open or extended position.

The slide arm is centrally channeled from the bottom, as at 15, to accommodate the screw with which the vise is ordinarily operated. This screw is eliminated when my apparatus is employed. Besides the elimination of the screw from the standard vise the only alterations which are necessary are the vertical channeling of the bracket 14, as at 16, and the transverse boring thereof, as at 17. I also transversely bore the slide arm 12 at spaced intervals, as at 18.

My operating mechanism, in addition to the vise provided as above described, comprises a right angled lever arm 19, the shorter arm whereof is slotted, as at 20, at its end to permit the passage of a removable pin 21 which is inserted through the desired bore 18 in the slide arm. Below the slot 20 in the short arm of the right angled lever is a bore 22 through which passes a pivot pin 23 inserted through the transverse bore 17 in the bracket 14.

The upper edge of the long arm of the right angled lever is transversely slotted at intervals, as at 24. I provide a weight 25 channelled to permit the passage of the long arm of the right angled lever and also to permit the passage of a latch strap 26. The rear end of this latch strap 26 is bent upwardly and forwardly, as at 27, to impinge against the weight 25 and prevent it from sliding off of the arm. The forward end of the latch strap is bent downwardly as at 26a, to enter one of the slots 24.

It will now be seen that the weight 25 on the long arm of the lever arm 19 pivoting on the pin 23 will force the movable vise jaw 13 toward the stationary lever jaw 10. To

operate the lever to release the vise I provide the treadle arm 29 with the right angled lower end 30 upon which the foot is placed. The upper end of the treadle is bent over to provide the hook 31 for engaging the long arm of the right angled lever 19. A headed pin 32 is provided in the long arm of the right angled lever arm and a stop pin 33 is provided adjacent thereto. The upper portion 10 of the treadle is inserted under the head of the pin 32 and against the stop pin 33 and drawn downwardly until the hook 31 engages the right angled lever 19, which renders the treadle rigid with respect to the lever arm 15 until the hook 31 is disengaged therefrom.

To adjust the vise for a particular piece of work the treadle arm is pushed inwardly sufficiently far to permit the withdrawal of the removable pin 21. The slide arm 12 is 20 then either pulled out or pushed in the requisite distance and the removable pin is again inserted through the bore 18, which is then opposite to the slot 20 in the upper end of the short arm of the right angled lever 25. Also, it may be desirable to adjust the weight 25, which is done by removing the projection 26a of the latch strap for the slot 30 24 in which it is inserted and moving the weight backward or forward to the approximate correct position which will permit the projection 26a of the latch to engage a slot 24 in the top of the long arm of the right angled lever.

Having described my invention what I 35 claim as new and desire to secure by Letters Patent is:

1. In combination with a vise having a transversely slotted base and an integral fixed jaw and a movable jaw carried by a 40 slide co-operating with the slot in said base, a right angled lever pivoted to said base and detachably connected with said slide arm, a weight co-operating with said right angled lever and a treadle depending from said 45 lever.
2. In combination with a vise having a slotted base and an integral fixed jaw, and a movable jaw carried by a centrally channelled slide arm co-operating with the trans- 50 verse slot in said base, a right angled lever arm pivoted in the slot of said slide and to said base, a weight co-operating with said lever arm and a treadle extending from said lever arm.
